UNITED STATES PATENT OFFICE.

DICKERSON G. BAKER, OF WILLIMANTIC, CONNECTICUT, ASSIGNOR TO THE WILLIMANTIC LINEN COMPANY, OF SAME PLACE.

MACHINE FOR WINDING COPS OF THREAD.

SPECIFICATION forming part of Letters Patent No. 617,071, dated January 3, 1899.

Application filed May 4, 1896. Renewed March 25, 1898. Serial No. 675,196. (No model.)

To all whom it may concern:

Be it known that I, DICKERSON G. BAKER, of Willimantic, in the county of Windham and State of Connecticut, have invented a new and useful Improvement in Machines for Winding Cops of Thread, of which the following is a specification.

My invention relates to an improvement in machines for winding cops of thread in which provision is made for successively winding cops or sets of cops upon a spindle and automatically ejecting the wound cops from the spindle as soon as they have reached the desired dimensions.

My invention contemplates in its broadest sense means for automatically starting the winding of cops of thread after the completion of previously-wound cops by providing for automatically connecting with the spindle the threads which lead from the source of supply to the previously-wound cop.

My invention further contemplates means for automatically distributing the power among independent sets of operating mechanisms.

A machine embodying the principles of my invention is herein shown and described and is particularly adapted to the winding of what are termed "solid" cops directly upon the winding-spindle as differentiated from the winding of bobbins on a hollow core, and I have shown in connection therewith a cop-ejecting mechanism controlled by the wound cop or cops and so interrelated with the movement of the winding-spindle that the movement of the latter is interrupted, while the discharge of the wound cop or cops is effected and promptly resumed as soon as the discharge has taken place.

In the accompanying drawings, Figure 1 is a view of the machine in side elevation. Fig. 2 is a top plan view. Fig. 3 is an end view looking from the left toward the right as the drawing is held in reading. Fig. 4 is an end view looking from the right toward the left as the drawing is held in reading. Fig. 5 is a vertical transverse section on the line 5-5 of Fig. 1. Fig. 6 is a top plan view of the mechanism for stopping and releasing the shaft which drives the spindle and for starting and stopping the shaft which operates

the ejector or discharge mechanism. Fig. 7 represents a reducing-gear, forming a connection between the drive-shaft and the spindle-shaft for varying the rotations of the spindle-shaft with respect to the number of vibrations of the thread-guide; and Fig. 8 is a vertical longitudinal section through the machine.

The frame for supporting the working parts of the machine may be of any suitable size and shape, as the particular conditions may require. In the present instance it is shown as consisting of a pair of heavy end standards A A', connected by a bed-piece A². The drive-shaft B is mounted in suitable bearings in the uprights A A' and is actuated by a drive-pulley b, fixed thereon, which is connected with a suitable source of power (not shown) by a belt b'.

The drive-shaft B communicates a vibrating motion to the thread-guide by means of a cam-disk C, fixed thereon and provided with a slanting face c, which bears against shoes d d', diametrically disposed upon the outer face of a yoke D, pivotally secured upon opposite sides of the shaft B by pivots d² to the sleeve d³, mounted on the shaft B. The shoes d d' may be conveniently attached to the yoke D by inserting their shanks in split sockets d⁴ d⁵ and clamping them therein by means of set-screws d⁶ d⁷, so that they may be adjusted at different distances from the center of the cam-disk C to vary the throw of the thread-guide or to suit cam-disks C of varying diameters.

The shank e of the thread-guide E is fixed in the top of the yoke D, and its upper edge may be provided with any desired number of slots e' for the reception of the threads leading from a suitable supply. (Not shown.) In the present instance the guide E is shown as provided with five slots e' and is adapted to simultaneously wind five cops on the spindle. It is obvious that a less number than five might be wound by leaving certain of the slots e' out of use for the time being and that a greater number might be wound at the same time by introducing in the place of the guide E a similar guide provided with more than five slots. The vibration of the guide E in the plane parallel with the axis of the shaft

B will be made positive by the engagement of the cam C with the shoes at the diametrically opposite points of the yoke, since the thicker portion of the cam-disk will alternately come into contact with the shoe upon the upper and lower sides of the said yoke.

- The connection of the yoke D with the sleeve d^3 , while permitting the thread-guide to freely vibrate in one direction, is such as to cause 10 the sleeve d^3 to positively rock on the shaft B as the guide E is forced away from the winding-spindle by the gradual increase in size of the cops being wound, and this rocking motion of the sleeve d^3 is utilized for the 15 purpose of determining the point at which the winding of the cop shall terminate by simultaneously effecting the stopping of the rotary movement of the winding-spindle and setting in motion the ejecting mechanism for 20 removing the cops from the spindle, as will hereinafter more particularly appear.

The spindle-shaft is denoted by F. It is mounted in suitable bearings in the standards A A' and is driven from the shaft B by intermeshing gear-wheels f and b^2 , fixed, respectively, on the shafts F and B. The spindle G, on which the cops are to be wound, is fixed at one end in the end of the shaft F, and its opposite end projects within a cop-receiving tube 30 g , provided with a friction tongue or tongues g' , projecting a slight distance from its interior surface along that portion of the tube adjacent to the terminal point of the spindle G. The thread-guide E for directing the 35 threads to the winding-spindle G is located between the receiving end of the tube g and the base of the winding-spindle G, and the spindle itself projects within the tube g a distance sufficient to permit a set of 40 cops which may be simultaneously wound on the spindle to be shifted along the spindle within the tube g without escaping from the end of the spindle while a new set of cops is being wound upon the spindle. It is to be 45 understood that in speaking of a set of cops I intend to include the winding of a single cop at any time in place of a plurality if for any cause it should be found preferable so to do. From what has hereinabove been stated it 50 will be seen that the arrangement is such that when a set of cops just wound is slid longitudinally along the spindle toward its free end within the tube g , by means of an ejecting mechanism which will be hereinafter particularly described, it will force a previous 55 set of cops which has been temporarily permitted to remain on the spindle G, within the tube g , off the end of the spindle into that portion of the cop-receiving tube g which is 60 somewhat contracted by the tongues g' . This will hold the set of cops which has been discharged from the spindle against a rotary movement, and the result will be that the threads connecting the individual members of 65 the set of cops which is held within the tube with the set of cops located on the spindle G, within the mouth of the tube, will be twisted

off intermediate of the members of the two sets of cops, one held within the tube and the other rotating on the spindle, while a new set 70 of cops is being wound on the spindle opposite the guide E.

The ejector consists of a depending arm H, embracing at its lower end the spindle G and fixed at its upper end to a longitudinally-reciprocating bar h , mounted in suitable bearings in the upper portions of the standards A A' and operated by a depending stud h' , preferably provided with an antifriction-roller, as is common, which enters a cam-groove h^2 in 80 the face of a drum h^3 , fixed to rotate with the sleeve h^4 , mounted on a tubular box f' , within which the spindle-shaft F rotates. The sleeve h^4 has also fixed to rotate therewith a worm-wheel h^5 , which is driven by a worm h^6 on a vertical shaft h^7 , the latter being provided with a worm-wheel h^8 , which is driven by a worm b^3 on the sleeve b^4 , mounted on a tubular box b^5 , within which the shaft B rotates, and provided with a clutch member b^6 , which 90 engages a clutch member b^7 on a sleeve b^8 on the shaft B, and having fixed to rotate therewith a drive-pulley b^9 , adjacent to the drive-pulley b , hereinbefore referred to. The sleeve b^4 , carrying the clutch member b^6 , is pressed 95 toward the clutch member b^7 by means of a spring b^{10} , and the effect of the spring-pressure upon the member b^7 is regulated by means of a tail-nut b^{11} , mounted on the screw-threaded end of the nipple b^{12} , which surrounds the sleeve b^8 and is held in position by a clamping-plate b^{13} . As the tail-nut b^{11} is turned in one direction on the nipple b^{12} it will force the clutch member b^6 away from the member b^7 against the tension of the spring b^{10} , and as it is turned in the opposite direction it will permit the spring b^{10} to exert a greater pressure upon the member b^7 . It follows, therefore, that when the drive-belt b' is shifted from the drive-pulley b onto the drive-pulley b^9 the rotary movement of the sleeve b^8 imparted to the clutch members and to the sleeve b^4 will rotate the worm b^3 , and hence the worm-wheel h^8 , and hence the worm h^6 on the shaft h^7 , and hence the worm-wheel h^5 on 115 the sleeve h^4 , carrying the drum h^3 , which by its rotation will force the bar h , carrying the ejector, to the limit of its advance stroke to crowd a set of cops into the mouth of the tube g and back again into normal position. 120 (Shown in Fig. 1.)

The drive-belt is automatically shifted at the proper intervals from the drive-pulley b onto the pulley b^9 and back again onto the pulley b by mechanism under the control of 125 the guide E, as follows: A drum K is mounted on the sleeve h^4 , with one of its ends adjacent to the end of the drum h^3 , and in the periphery of the drum K there is formed a cam-groove k for the reception of a stud k' , projecting from the arm l of a belt-shifting lever pivoted to a suitable support at L and having its arm l' provided with a cross-head l^2 , carrying a pair of studs or pins $l^3 l^4$ for en-

gaging the opposite edges of the belt b' . The drum K is held under spring tension tending to rotate it in a direction to shift the belt from the drive-pulley b onto the drive-pulley b^9 by means of a coil-spring k^2 , (see Fig. 5,) one end of said spring being secured to the sleeve h^4 , which rotates with the drum h^3 , and the opposite end to the drum K. The drum K is, however, prevented from rotating under 10 the tension of the spring k^2 , except at the desired intervals, by means of a catch I, fixed to rock with the sleeve d^3 , to which the guide E is yoked, the nose i of said catch I (see Fig. 3) being adapted to engage a shoulder k^3 on 15 a cam-disk k^4 , fixed to rotate with the drum K. The catch I is held against the periphery of the cam k^4 and the guide E against the periphery of the cop being wound at the desired pressure by a spring or weight, in the present 20 instance by a spring R, connected with the end of an arm r, projecting from the sleeve, which carries the catch I and the guide.

From the above construction it follows that as the guide E is forced away from the spindle by the gradual increase in diameter of the cops which are being wound it will rock the sleeve d^3 , and hence the catch I, gradually away from the cam-disk k^4 until when the cop has reached the desired diameter the 25 nose i of the catch will escape from the shoulder k^3 , and thereby set the drum K free to rotate under the tension of the spring. As the drum K rotates it will during its first half-revolution rock the belt-shifting lever in a 30 direction to shift the belt from the pulley b onto the pulley b^9 , and the rotary movement of the drum K will be temporarily arrested at the limit of such half-revolution to hold the belt for a time upon the pulley b^9 by 35 means of the engagement of a lug k^5 on the periphery of the drum K, adjacent to the end of the drum k^3 , with the nose m of a spring-actuated dog M pivoted to a suitable support at m' . (See Fig. 5.) The said drum K 40 will be again released and permitted to complete its revolution under the tension of the spring k^2 when the drum h^3 nears the completion of its revolution by the engagement of a lug k^6 on its periphery adjacent to the 45 end of the drum K with the nose m of the dog M. The outer end of the lug k^6 is rounded, so that it will not catch the nose of the dog, but will pass beneath it and gradually lift it back out of engagement with the 50 lug k^5 on the drum K. It is obvious that that portion of the nose m of the dog M which is opposite the lug k^6 on the drum h^3 might be rounded and the lug k^6 left squared, if such reversal were found desirable. When 55 the drum K is so released by the rotary movement of the drum h^3 , it will complete its second half-revolution and in so doing will rock the lever L into the position shown in Fig. 1 to shift the belt back again from the pulley 60 b^9 onto the pulley b , and thus will again start the rotary movement of the spindle. Since the actuating-spring k^2 is secured at one end

to the sleeve h^4 , which rotates together with the drum h^3 , the rotary movement of said drum h^3 will serve to wind the spring and keep 70 it wound, so that it is at all times ready for action to turn the drum K. The drive-pulleys b and b^9 are promptly brought to a stop, when the belt is released therefrom, by means of brakes S and S', which are slid toward the 75 faces of the pulleys by the inclined ends of the belt-shifting pins $l^3 l^4$, with the beveled ends $s s'$ of the sliding brakes S S' as the belt-shifting lever is rocked back and forth. The sliding brakes S S' are promptly thrown 80 out of engagement with their respective pulleys when released by the belt-shifting pins or studs $l^3 l^4$ by the frictional engagement of the face of the pulley with the brake, tending to slide it away from its face. The relation of the belt-shifter to the brakes is clearly 85 shown in the detail plan view, Fig 6. The tension device for holding the several threads under the proper strain as they are fed to the winding-spindle is here shown as consisting 90 of a series of glass or other highly-polished disks O, held pressed toward one another by a spring o, the tension of which may be increased or diminished at pleasure by means of a thumb-nut P. 95

To keep the face of the cam-disk C properly lubricated along the path where it bears against the shoes upon the yoke which carries the guide E, I find it convenient to provide a stick of graphite or other suitable lubricating material Q, supported in a suitable socket q, projecting from the standard and pressed gently against the face of the disk by a spring q' within the socket. 100

The intermeshing gears f and b^2 may be 105 relatively varied at pleasure to make the number of rotations of the spindle correspond to or vary from the number of vibratory movements of the guide E as may be found desirable. In the form shown in Fig. 7 provision is made for driving the spindle-shaft F a little slower than the drive-shaft B by making the gear-wheel F' corresponding to the gear-wheel f in Fig. 1 a little smaller than the gear-wheel B' corresponding to the gear 110 b^2 in Fig. 1. This will make the vibratory movement of the guide E and the rotary movement of the spindle non-synchronous, so that the diagonal position of the thread 115 across the periphery of the cop being wound will vary its position during the successive rotations of the cop and add to its firmness. 120

The operation of the several parts of the machine have been so fully set forth in connection with the foregoing description that 125 a further detailed statement of the operation is not deemed necessary. The operation may, however, be concisely stated as follows: As soon as the set of cops has been wound on the spindle G of sufficient size to press the 130 guide E back to a point where the catch I will release the disk k^4 and hence the drum K, the latter will complete a half-revolution and shift the belt from the pulley b to the

- pulley b^9 and thereby start the rotary movement of the sleeve b^8 and hence the rotary movement of the drum h^3 by the intermediate connection of worm-wheels and worms.
- 5 The rotary movement of the drum h^3 will advance the ejector H and slide the set of cops already wound into the end of the tube g . As the drum h^3 nears the completion of its revolution it will set free the drum K , which 10 has already been arrested at a half-revolution by the spring-actuated dog M , and the said drum K will complete its revolution under the tension of its actuating-spring and will again shift the belt from the pulley b^9 15 onto the pulley b and hence start the winding of a new set of cops. The drum K will be arrested at the completion of its revolution by means of the catch I , the nose of which will catch over the shoulder k^3 , as 20 clearly shown in Fig. 3. As the second set of cops is slid along the spindle G by the ejector H it will crowd the set previously wound off the spindle into the contracted portion of the tube G , where they will be 25 held against a rotary movement, while the rotary movement of the set subsequently wound during the winding of a succeeding set will twist apart the threads which unite the members of the discharged set of cops 30 with the members of the set on the spindle within the end of the tube. In this manner the machine will automatically proceed to wind set after set, eject them from the spindle, and sever the threads which connect them 35 with those which have been previously wound.
- It will be observed that by throwing apart the clutch members which connect the sleeves for transmitting motion from the drive-pulley b^9 to the ejecting mechanism, the belt being 40 at the time on the drive-pulley b^9 , the sleeve-section which carries the pulley b^9 will be permitted to rotate idly and the operation of the machine will be stopped without stopping the drive-belt b' .
- 45 In using the expression "belt-shifter" in the foregoing description I wish to be understood as including such means as the well-known ordinary shifting-clutch for distributing power among independent sets of operating mechanisms.
- 50 What I claim is—
1. The combination with cop-winding mechanism, including a winding-spindle having one end free for the discharge of wound cops 55 therefrom, a thread-guide and means for imparting motion to the spindle and guide, of a cop-receiver at the free end of the spindle and means for discharging wound cops by successive movements, first toward the free 60 end of the spindle to continue their rotary movement during the starting of the winding of a new set of cops, and subsequently off the free end of the spindle, substantially as set forth.
  - 65 2. The combination with cop-winding mechanism, including a winding-spindle having an end free for the discharge of wound cops

therefrom, a thread-guide, means for imparting to the thread-guide a vibrating movement during each revolution of the winding-spindle 70 and means for rotating the spindle, of a cop-receiver at the free end of the spindle and means for discharging the wound cops by successive movements toward and off the free end of the spindle, substantially as set forth. 75

3. In combination, several independent operating mechanisms, an actuating mechanism common to the several independent operating mechanisms, a spring-actuated rotary cam for distributing power from said common actuating mechanism among the said independent operating mechanisms, means for automatically winding said spring-actuated cam and means for automatically stopping and releasing said cam. 85

4. A cop-winding machine, comprising a winding mechanism including a rotary spindle, means for guiding the thread to the winding mechanism, means for ejecting the wound cops and a cop-retaining device for holding 90 a previously-wound cop while a subsequently-wound cop is rotated by the spindle to sever the thread between the cops, substantially as set forth.

5. A cop-winding machine, comprising a 95 winding-spindle, means for operating it, a cop-receiving tube at the free end of the spindle and provided with a contracted portion in position to engage the cop as it leaves the spindle, means for guiding the thread to the 100 spindle and means for sliding the wound cops from the spindle into the said cop-receiving tube, whereby the thread connecting the cop within the contracted portion of the tube and the wound cop on the spindle is twisted apart, 105 substantially as set forth.

6. In combination, a drive-shaft, a spindle-shaft, gears connecting the said shafts, a cop-ejector and a thread-guide, the said thread-guide being under the control of the wound 110 cop to stop the spindle-shaft and operate the cop-ejector, substantially as set forth.

7. In combination, a winding mechanism, an ejecting mechanism, mechanism actuated by the cop for controlling the winding and 115 ejecting mechanisms, to stop the winding and start the ejecting mechanism and means under the control of the ejecting mechanism to start the winding mechanism, substantially as set forth. 120

8. In combination, a winding mechanism, an ejecting mechanism, pulleys for transmitting motion to said mechanisms a drive-belt, a belt-shifter for moving the belt back and forth on the pulleys to alternately actuate 125 the winding and the ejecting mechanisms, a spring-actuated rotary cam for operating the belt-shifter, the said rotary cam being under the control of the cop being wound to release the said cam, to start the ejecting mechanism, and under the control of the ejecting mechanism to release the said cam to start the winding mechanism, substantially as set forth. 130

9. In combination, a drive-shaft, a spindle-

- shaft driven thereby, an ejector, a rotary cam for operating the ejector, drive-pulleys one for actuating the drive-shaft and one for actuating the ejector-operating cam, a belt-shifter for throwing the belt alternately into engagement with the drive-pulleys, a spring-actuated rotary cam for operating the belt-shifter and stops under the control respectively of the cop being wound and the ejector-operating cam for releasing the belt-shifter-operating cam, substantially as set forth.
10. The combination with the belt-shifter and cop-ejector and the rotary cams for operating them, of a spring for actuating the belt-shifter-operating cam, the said spring being connected with the ejector-operating cam whereby the movement of the latter winds up the spring after the former has utilized its force, substantially as set forth.
- 15 11. The combination with the drive-shaft, the sleeve mounted thereon and the thread-guide having its arm pivoted to the sleeve to vibrate in a plane parallel with the axis of the sleeve, of an oblique-faced disk fixed to the drive-shaft and having a bearing against the guide-arm upon opposite sides of its axis of vibration, substantially as set forth.
- 20 12. The combination with the drive-shaft, the sleeve mounted thereon and the thread-guide pivoted to the sleeve to vibrate in a plane parallel with the axis of the sleeve, of an oblique-faced disk fixed to the drive-shaft, bearing-shoes upon opposite sides of the axis of vibration of the thread-guide and means for 25 adjusting the bearing-shoes toward and away from the axis of rotation of the said disk to vary the movement of the thread-guide, substantially as set forth.
- 30 13. The combination with the winding mechanism, the ejecting mechanism and their respective drive-pulleys, of sleeve-sections

provided with clutch members and forming a separable connection between the ejecting mechanism and its drive-pulley, substantially as set forth.

45

14. The combination with the winding mechanism, the ejecting mechanism and their respective drive-pulleys, of sleeve-sections provided with friction-clutch members and forming a separable connection between the ejecting mechanism and its drive-pulley and means for varying the frictional contact of the said clutch members, substantially as set forth.

50

15. The combination with the drive-pulleys and the belt-shifting pins, of brakes supported to move toward and away from the drive-pulleys and provided with beveled surfaces in position to be engaged by the belt-shifting pins or legs to force them alternately toward the pulley from which the belt is removed, substantially as set forth.

55

16. The combination with the spindle-shaft and the drive-shaft geared thereto, of the ejector, its rotary operating-cam, mounted concentric with the spindle-shaft, the belt-shifter, its rotary operating-cam mounted concentric with the spindle-shaft, a drive-pulley on the drive-shaft, a sleeve concentric with the drive-shaft a drive-pulley on said sleeve, 70 worm-gear connecting the said pulley-carrying sleeve with the ejector-operating cam, the spindle, means under the control of a cop being wound on the spindle to operate the belt-shifter and means under the control of the 75 ejector-operating cam for actuating the belt-shifter-operating cam, substantially as set forth.
